SELF-SIZING JOINTED WRIST-ENCIRCLING BRACELET

William P. Canning, Woodbury, Conn., assignor to Benrus
Watch Company, Inc., New York, N. Y., a corpora-
tion of New York

Application June 5, 1952, Serial No. 291,959

24 Claims. (Cl. 63—9)

The present invention relates to the construction of a jointed bracelet so that the jointed portions thereof will resiliently accommodate themselves to the size and shape of the wearer's wrist. It is here specifically disclosed as used with a wrist watch and adapted to secure the watch to the wearer's wrist, but it is susceptible of more generalized uses as well.

One type of wrist watch bracelet which has become exceedingly popular takes the form of a pair of rigid curved claws pivotally attached to the ends of a watch case and adapted, in conjunction with the watch case, to encircle a major portion of the wrist of the wearer and thus hold the watch in place, the claws being spreadable to permit the wearer's wrist to escape from between the claws when it is desired to remove the watch from the wrist. One drawback inherent in this type of construction is the fact that the wrists of individuals vary widely as to size and shape, and a claw configuration producable on a mass production basis cannot fit every wrist snugly and smoothly.

Resiliently jointed bracelets, and even resiliently jointed watch bracelets, have been known in the past, but they have not been widely used because their construction did not lend itself to the use of sturdy parts nor to the ready assemblability which is so necessary if such structures are to be produced on a quantity basis and at a competitive price. In particular, the use of helically coiled springs surrounding the pivoted joint between adjacent bracelet elements has not proved entirely practical because the limited space available for such springs has necessitated the fabrication of the springs from thin, and consequently comparatively flimsy, material, thus giving rise to a weak wrist encircling force and to frequent breakage. The use of leaf springs extending between adjacent bracelet elements has been proposed, those springs being considerably sturdier and hence more dependable than the helically coiled springs previously mentioned, but the problems involved in mounting those leaf springs with respect to the bracelet elements have prevented the widespread or effective adoption of this expedient.

The structure of the present invention permits the use of a sturdy spring having the desirable characteristics of both the helically coiled and leaf springs but without the disadvantages previously attendant upon their use. In particular, the springs employed in the present invention are formed and mounted independently of the pivotal connection between adjacent bracelet elements, those elements being made in the form of shells and the springs being readily insertable into the shells as they are assembled to form the finished bracelet. The springs cooperate with the interior of the shells in a novel and effective manner so as to be held in place without having to provide any special holding means in the shell, and act in a positive and effective manner so as to urge the bracelet elements or shells into wrist-encircling position. More specifically, the shells nest within one another and are pivotally connected to one another at their

2

internested portions, the shells being provided with open mouths at their ends through which portions of the springs may extend from one shell to the next. The springs themselves are provided with portions, usually in the form of coils which add to the resiliency and dependability of action of the springs, which are insertable into the shells from one end thereof but not through the other end thereof, those portions abutting the shell end through which they cannot pass so as to limit the direction of movement of the springs toward that shell end. Other portions of the springs engage with elements on the interior of the shells (not provided specially for that purpose) so as to limit the movement of the springs with respect to the shells in the opposite direction, thus fixing the relative position of the springs and shells.

Where, as is here specifically disclosed, the bracelet is in two separable parts comparable to the rigid claws previously described as utilized in a particular type of watch bracelet, the terminal links or shells of the bracelet are closed at their free ends, their other ends, which are received within and pivotally mounted in the adjacent regular shells, having an open mouth through which a spring portion may extend, the spring active upon these terminal shells being preferably held in position by being interlocked with a portion, and preferably the coiled portion, of the next adjacent spring.

By reason of the construction thus described, a jointed bracelet is produced which will, in a uniformly dependable manner, resiliently grasp the wrist of the wearer and conform itself to the size and shape thereof, this bracelet being constructed of a minimum number of simply constructed elements, all well adapted to mass production, which elements may be assembled in a notably simple, rapid and foolproof manner.

To the accomplishment of the above and to such other objects as may hereinafter appear, the present invention relates to a jointed bracelet construction as defined in the appended claims, and as described in this specification, taken together with the accompanying drawings, in which:

Fig. 1 is a three-quarter perspective view of the bracelet of the present invention in use on the wrist of a wearer, the invention being shown as a watch bracelet;

Figs. 2 and 3 are idealized views showing the manner in which the bracelet construction will adapt itself to wrists of different sizes and shapes, Fig. 2 showing the bracelet encircling a narrow wrist and Fig. 3 showing the bracelet encircling a thinner but wider wrist;

Fig. 4 is an end cross sectional view taken along the line 4—4 of Fig. 1;

Fig. 5 is a top plan view of one of the standard spring units employed in that bracelet;

Fig. 6 is a front elevational view of the spring of Fig. 5;

Fig. 7 is a top plan view of a spring specifically designed for use with the terminal link of that bracelet;

Fig. 8 is a top cross sectional view taken along the line 8—8 of Fig. 4;

Fig. 9 is a view similar to Fig. 4 but showing a specifically different construction;

Fig. 10 is a top plan view of one of the standard spring units employed in the bracelet of Fig. 9;

Fig. 11 is a front elevational view of the spring of Fig. 10;

Fig. 12 is a top plan view of a spring specifically designed for use with the terminal link of the bracelet of Fig. 9; and

Fig. 13 is a front elevational view of the spring of Fig. 12.

Having reference first to the embodiment of Figs. 1—8, the bracelet comprises a plurality of hollow shells 2 each internested with adjacent shells and being pivotally connected thereto, the uppermost shell 2 being internested

with and pivotally connected to a link 4, preferably of comparable shape, which is fixed to the watch case 6. The bracelet is here disclosed in the form of a pair of jointed claws generally designated 7 and 7' depending from the watch case 6, the ends of each of these claws being defined by a terminal shell 8 partially received within and being pivotally connected to the last or lowermost regular shell 2'.

All of the shells are provided with a large end 10 and a small end 12, the large end 10 having an open mouth 14 of a width at least equal to the width of the small shell ends 12 but being less than the width of the large shell ends 10. The small shell ends 12 pass through the mouths 14 of adjacent shells and are received within the large ends 10 of those adjacent shells, there being pivotally connected to said adjacent shells by means of pins 16.

The height of the mouths 14 is sufficiently greater than the height of the shell portions passing therethrough so that each of the shell has a limited degree of pivotal motion relative to adjacent shells. Each of the shells 2, 2' and 8 are provided, at their small ends 12 with open mouths 18, these mouths having a restricted height, as may best be seen from Fig. 4, which is appreciably less than the height of the open mouths 14 at the large shell ends 10. For obvious reasons, the small end 12 of the shell 4 need not be provided with any mouth at all, and the large end 10 of the terminal shell 8 should not be provided with any mouth, but should be completely closed by an end wall 25 for purposes of appearance and in order to protect the bracelet.

In order to cause the shells 2, 2' and 8 to pivot in a wrist-encircling and -engaging direction, springs are mounted inside the bracelet, these springs being active on the shells so as to cause them to pivot in a clockwise direction as viewed in Figs. 1 and 4, when the right hand claw 7 is considered, and in a counter-clockwise direction, as viewed in Figs. 2 and 3, when the left hand claw 7' is considered. The springs employed in the regular shells 2 and 2' are shown in Figs. 5 and 6, one such spring being used for each shell 2 or 2'. These springs comprise a pair of divergent arms 20, a pair of spaced coils 22, one at the end of each of the arms 20, and a reversely bent section 24 joining the coils 22 and extending therefrom to the opposite side thereof from the arms 20 but at an angle to those arms 20, as may best be seen from Fig. 6. The spring is formed of any suitable resilient material such as high tensile stainless steel spring wire, and for purposes of sturdiness this wire may have an appreciable diameter such as, for example, .015 inch.

The coils 22 are not passable through the mouth 18 at the small end 12 of the shells 2, either because their height is greater than the height of the mouth 18, their lateral spacing is greater than the width of the mouth 18, or both. The length of the arms 20 is such that when a given spring is inserted into a shell 2 or 2' through the mouth 14 at the large end 10 thereof, which mouth 14 is of sufficient size to permit such entrance, the spring being passed through the shell 2 until the coils 22 abut the small mouth 18, the diverging tips of the arms 20 will snap into place against the end wall 25 at the large end 10 of the shell 2 or 2' on either side of the mouth 14. In this manner the springs will be securely held in place in the shells 2 or 2', upward movement in Fig. 4 being prevented by engagement between the coils 22 and the mouth 18, and downward movement being prevented by engagement between the arms 20 and the shell end walls 25. When a spring is in this locked position, its reversely bent portion 24 will extend out of the shell 2 or 2' via the mouth 18 and into the next adjacent shell 2 or 4, where it will engage against the bottom wall 27 thereof after being bent from its angular position relative to the arms 20, as shown in Fig. 6, to a more closely parallel position as shown in Fig. 4, the coils 22 twisting to permit this and the

spring thus acting resiliently upon the shells so as to urge them to pivot to a wrist-engaging and -encircling position. The pivotal movement of each shell with respect to the shell to which it is pivotally connected will be limited by the height of the mouth 14, clockwise movement in Fig. 4 being limited by engagement between the bottom wall 27 of a shell with the bottom of the mouth 14 and pivotal movement in a counter-clockwise direction against the action of the springs being limited by engagement between the top wall 29 of a shell and the upper edge of the mouth 14.

Since the terminal link 8 does not have an open mouth at the large end 10 thereof, a spring of specifically different design must be employed therewith, that spring being shown in Fig. 7. It comprises a pair of divergent arms 26 having laterally directed fingers 28 at the free ends thereof, the other ends of the arms 26 being connected to coils 30 which are in turn connected by means of a reversely bent portion 32 corresponding to the reversely bent portion 24 of the other springs. The spring of Fig. 6 is adapted to be secured in place by causing the arms 26 to pass between the coils 22 of the spring in the adjacent regular shell 2', the fingers 28 being received inside said coils 22. The engagement between the fingers 28 and the coils 22 serve to lock the spring of Fig. 7 in position. The reversely bent portion 32 will freely enter the terminal link 8 via its restricted mouth 18, even though the coils 30 cannot pass through that mouth, the reversely bent portion 32 thus acting upon the bottom wall 27 of the terminal link 8 so as to swing that link into wrist-encircling engagement.

The manner of assembly of the bracelet of Figs. 1-8 will in the main be apparent from the above description of its construction. Assembly is progressively accomplished. The uppermost link 2 is telescoped with respect to the link 4, and is pivotally connected thereto by means of the pin 16. The spring of Figs. 5 and 6 is then inserted into the shell 2 via the mouth 14 thereof and with the reversely bent section 24 foremost, that section passing through the restricted mouth 18 and into the shell 4 while the coils 22 of the spring approach the restricted mouth 18. When the spring has been fully inserted into the shell 2, the coils 22 abutting against the mouth 18, the arms 20 will have passed through the mouth 14 and sprung apart so as to engage against the shell end wall 25, thus fixing the position of the spring with respect to the shell 2. This sequence of operations is continued until the last regular shell 2' has been secured in place and its spring has been inserted, the reversely bent sections 24 of the several springs being received between the diverging arms 20 of the preceding spring. The spring of Fig. 7 is then secured in place by causing its fingers 28 to engage inside the coiled portions 22 of the preceding spring within the shell 2', the reversely bent portion 32 of the spring of Fig. 7 extending downwardly out through the mouth 14 of the last regular shell 2'. The terminal shell 8 is then telescoped within said last regular shell 2' and is pivotally secured in place by means of a pin 16, the reversely bent section 32 of the spring of Fig. 7 passing inside the terminal shell 8 via the mouth 18 at the small end 12 thereof.

The bracelet of Figs. 9-13 is constructed and assembled in substantially the same manner, except that different springs are employed. It will be noted, however, that the shells of the bracelet of Fig. 9 are of specifically different shape than the shells of the bracelet of Fig. 4, and that the shells of the bracelet of Fig. 9 are pivotally secured together in a specifically different manner, the shells of Fig. 9 being provided with bushings 34 at the small ends 12 thereof through which the pins 16 are adapted to pass, these bushings projecting above the top walls 29 of the shells, whereas in Fig. 4 the pins 16 merely pass through the side walls 31 of the shells at their small ends 12.

The springs employed for the regular shells 2 and 2' of the bracelet of Fig. 9 are defined by a coil 36 from the

opposite ends of which long arm 38 and short arm 40 extend in opposite directions and at angles to one another, the long arm 38 terminating in a hook 42. As in the previously described embodiment, the coil 36 is of a size such that it cannot pass through the comparatively restricted mouth 18 at the small end 12 of the shells 2 or 2', the restricted nature of that mouth 18 being defined in part by the bushing 34 as here specifically disclosed. Hence the spring for the uppermost shell 2 is first caused to enter the shell 4 via the comparatively expansive mouth 14 at the large end 10 thereof, the short arm 40 and the coil 36 being received within the shell 4 past the point at which the shell 2 will be pivotally secured thereto. Thereafter the shell 2 is telescoped within the shell 4, the long arm 38 of the spring entering the shell 2 via the restricted mouth 18 thereof, and a pin 16 is passed through the bushing 34 on the shell 2 and through the side walls of the shell 4 in order to pivotally secure the shells together.

The spring for the next shell, here shown as the last regular shell 2', is then inserted into the already pivotally secured shell 2 via the mouth 14 thereof, and the next shell 2' is then telescoped within the pivotally secured to the first mentioned shell 2, care being taken that the hooked end 42 of the arm 38 of the first inserted spring engages over the bushing 34 on the second mentioned shell 2'. Movement of the springs with respect to the shells in an upward direction in Fig. 9 is limited by engagement between the hooked end 42 of the arm 38 and the bushing 34 on the appropriate shell, while movement of the spring with respect to the shell in the opposite direction is limited by engagement between the coil 36 thereof and the restricted mouth 18 of the appropriate shell. Even in absence of the bushing 34, movement of the spring with respect to the shell in an upward direction would be resisted by the curvature of the hooked end 42, the body of which is taller than the height of the mouth 18. To remove the spring in an upward direction a sufficiently strong pull would have to be exerted thereon, even after it had been pulled past the bushing 34, to cause the hooked end 42 to flatten out. This could be accomplished only manually in the course of emergency disassembly of the bracelet, but could not occur while the bracelet was in use.

In this construction the action of a given spring is exerted between one shell and the shell next removed. For example, taking the uppermost spring, its arm 40 is active on the initial shell 4 and its arm 38 is active on the upper surface of the shell 2'. It thus not only causes the shell 2 to pivot in a clockwise direction with respect to the initial shell 4, but also, because it engages the shell 2' at a point below the pin 16 which connects it to the shell 2, it causes the shell 2' to pivot in a clockwise direction with respect to the shell 2.

The spring useable with the terminal shell 8 of the bracelet of Fig. 9 is shown in Figs. 12 and 13. That spring comprises a coil 44, from the opposite ends of which extend arms 46 and 48, those arms extending to opposite sides of the coiled portion 44 and at angles to one another. The arm 46 is provided with an inwardly projecting finger 50 adapted to be received inside the coil 36 of the next adjacent spring. In assembling the terminal link 8, the spring of Figs. 12 and 13 is first inserted into and through the last of the regular shells 2' and into the next higher shell 2, the fingers 50 on the arm 46 being engaged inside the coil 36 of the adjacent regular spring, the coil 44 then being positioned within the last regular shell 2' inwardly of the point where the terminal shell 8 will be secured thereto. The terminal shell 8 is then telescoped within the last regular shell 2 and pivotally secured in position by means of pin 16. The arm 48 of the spring of Figs. 12 and 13 entering into the terminal shell 8 via the restricted mouth 18 at the small end 12 thereof, the spring thus causing the terminal link 8 to pivot into wrist-engaging pivoted position.

The degree to which the bracelet of the present invention will conform to the wrist of the wearer will depend upon the size and number of shells employed; the greater the number of shells the more closely will conformation take place. As may be seen from a comparison of Figs. 2 and 3, the bracelet will smoothly conform to wrist contours of various shapes and to wrists of various sizes, and without any unsightly gaps being formed, while at the same time the watch 6 will be firmly secured in place. When it is desired to remove the watch or bracelet from the wrist, the terminal links 8 need merely be spread apart, the other links also pivoting in an outward direction with respect to the wrist to the extent permitted by the mouths 14 and against the resilient action of the springs.

The bracelet components are of standard design and may be manufactured very inexpensively. The shells and springs are independently formed and independently assembled. Because small clearances and the use of small spaces is avoided, the springs may be comparatively massive, particularly when compared with prior art springs designed to perform a comparable function, and hence give greater resilient action with increased dependability and longer life. Because of the specific design of the springs and shells, assembly of the bracelet is facilitated and can be performed by operators with but a minimal amount of skill. Moreover, the assembly operation is relatively foolproof. For example, taking the embodiment of Figs. 1-8, when the divergent arms 20 pass within a given shell and snap beyond the mouth 14 thereof, the assembler will know that the spring is in its proper position. In the embodiment of Fig. 9, when the hooked end 42 of the arm 38 snaps over the top of the newly inserted shell, the operator will similarly know that the spring is in proper operative position.

While but two embodiments of the present invention have been here disclosed, both specifically designed for use as watch bracelets and to supplant or supplement the rigid claw-type bracelet now widely in use, it will be apparent that the construction in question may be utilized in bracelets of specifically different types and that wide variations in the details of the construction may be resorted to without departing from the spirit of the invention as defined in the following claims.

I claim:

1. In a jointed bracelet comprising a plurality of hollow shells having large and small ends and with open mouths at said ends, the small end of one shell being received inside the large end of an adjacent shell and pivotally mounted therein about an axis substantially perpendicular to the longitudinal axis of said bracelet, the size of the mouths at the large ends of said shells in the direction of pivotal movement of said shells being sufficient to permit a limited degree of relative pivotal movement; the improvement which comprised springs each comprising a body portion passing through one of said shells, a first operative portion passing through the narrow end of said one of said shells, entering into the adjacent shell and engaging the inside of said adjacent shell, and a second operative portion engageable inside one of said shells adjacent the large end thereof, said springs being active to urge said bracelet into wrist-engaging position, said springs having a part disposed out of registration with the open mouth at the narrow end of said one of said shells and engaging against said narrow end when said spring is moved theretoward, said spring being restrained from movement in one direction substantially parallel to the length of said bracelet by engagement between said spring part and said narrow shell end and in the opposite direction through engagement between said second operative portion and said large shell end.

2. In a jointed bracelet comprising a plurality of hollow shells having large and small ends and with open mouths at said ends, the small end of one shell being received inside the large end of an adjacent shell and piv-

totally mounted therein about an axis substantially perpendicular to the longitudinal axis of said bracelet, the size of the mouths at the large ends of said shells in the direction of pivotal movement of said shells being sufficient to permit a limited degree of relative pivotal movement; the improvement which comprises springs in said shells each comprising a pair of divergent arms the tips of which are seated at the large end of one of said shells to either side of the open mouth at said end, and a portion connecting said arms including a part which extends out through the narrow end of one of said shells, into the shell adjacent said narrow shell end and engaging an inner surface of said adjacent shell, said springs being active to urge said bracelet into a wrist-engaging position, said springs having a part disposed out of registration with the open mouth at the narrow end of said one of said shells and engaging against said narrow end when said spring is moved theretoward, said spring being restrained from movement in one direction substantially parallel to the length of said bracelet by engagement between said spring part and said narrow end and in the other direction to engagement between said divergent arms and said large shell end.

3. The jointed bracelet of claim 2, in which said arms and said part of said connecting portion are in planes out of line with one another.

4. The jointed bracelet of claim 2, in which said part of said connecting portion is received within said adjacent shell between the divergent arms of the next adjacent spring.

5. In a jointed bracelet comprising a plurality of hollow shells having large and small ends and with open mouths at said ends, the small end of one shell being received inside the large end of an adjacent shell and pivotally mounted therein about an axis substantially perpendicular to the longitudinal axis of said bracelet, the size of the mouths at the large ends of said shells in the direction of pivotal movement of said shells being sufficient to permit a limited degree of relative pivotal movement; the improvement which comprises springs in said shells each comprising a pair of divergent arms the tips of which are seated at the large end of one of said shells to either side of the open mouth thereat, and a portion connecting said arms and including a pair of spaced coils, one at the end of each of said arms, and a reversely bent section joining said coils and extending therefrom in a direction opposite from said arms and in a plane out of line with the plane of said arms, said reversely bent section extending into the shell adjacent the small end of said first named shell, said section engaging an inner surface of said adjacent shell, said springs being active on said bracelet so as to urge it into a wrist-engaging position, said springs having a part disposed out of registration with the open mouth at the narrow end of said one of said shells and engaging against said narrow end when said spring is moved theretoward, said spring being restrained from movement in one direction substantially parallel to the length of said bracelet by engagement between said spring part and said narrow end and in the other direction to engagement between said divergent arms and said large shell end.

6. The jointed bracelet of claim 5, in which said reversely bent section is positioned within said adjacent shell between the divergent arms of the adjacent spring.

7. In a jointed bracelet comprising a plurality of hollow shells having large and small ends and with open mouths at said ends, the small end of one shell being received inside the large end of an adjacent shell and pivotally mounted therein about an axis substantially perpendicular to the longitudinal axis of said bracelet, the size of the mouths at the large ends of said shells in the direction of pivotal movement of said shells being sufficient to permit a limited degree of relative pivotal movement; the improvement which comprises springs each passing substantially completely through one of said shells, engaging in the interior of said one of said shells adjacent its large

end so as to limit the permissible movement of said spring through said shell toward said end, and extending out through the narrow end of said shell into the next adjacent shell, said springs being active on said bracelet so as to urge it into a wrist-engaging position, said springs having a part disposed out of registration with the open mouth at the narrow end of said one of said shells and engaging against said narrow end when said spring is moved theretoward, thereby limiting the permissible movement of said spring through said shell toward said narrow end.

8. In combination with the bracelet of claim 5, a hollow terminal shell of shape comparable to the other shells but having an open mouth only at the small end thereof, said small end being received within and pivotally mounted with respect to the last of the other shells of said bracelet, and a spring comprising a pair of arms positioned alongside the spaced coils of the spring in said last of said other shells and having fingers engageable with said coils so as to hold said spring in position, and a portion connecting said arms and received inside said terminal shell, said spring being active to pivot said terminal shell with respect to said other shells into a wrist-engaging position.

9. In a jointed bracelet comprising a plurality of hollow shells having large and small ends and with open mouths at said ends, the small end of one shell being received inside the large end of an adjacent shell and pivotally mounted therein about an axis substantially perpendicular to the longitudinal axis of said bracelet, the size of the mouths at the large ends of said shells in the direction of pivotal movement of said shells being sufficient to permit a limited degree of relative movement; the improvement which comprises springs in said shells each comprising a coiled portion and a pair of operative portions extending to either side of said coiled portion and at angles to one another, said spring extending through adjacent shells, one of said operative portions extending substantially to the large end of one of said shells and there engaging said shell so as to limit the permissible movement of said spring relative to said shell in the direction of said end, the other of said operative portions extending into the adjacent shell, said springs being active on said bracelet so as to urge it into a wrist-engaging position, said springs having a part disposed out of registration with the open mouth at the narrow end of said one of said shells and engaging against said narrow end when said spring is moved theretoward, thereby limiting the permissible movement of said spring through said shell toward said narrow end.

10. In a jointed bracelet comprising a plurality of hollow shells having large and small ends and with open mouths at said ends, the open mouth at said large end having a dimension greater than the corresponding dimension of the open mouth at said small end, the small end of one shell being received inside the large end of an adjacent shell and pivotally mounted therein about an axis substantially perpendicular to the longitudinal axis of said bracelet; the improvement which comprises springs each comprising a stop portion extending out of the general configuration of said spring and a pair of operative portions extending in opposite direction from said stop portion and at angles to one another, said stop portion being passable through the open mouth at the large end of a shell but not being passable through the open mouth at the small end of said shell, said spring being positioned so that said stop portion is adjacent the open mouth at the small end of one of a pair of adjacent shells, thus limiting its movement relative to said shells in a direction toward said mouth, one of the operative portions of said spring extending within the interior of the shell in which said coiled portion is received and the other of said operative portions extending through said adjacent open mouth and into the adjacent shell, said springs being active on said bracelet so as to urge it into a wrist-engaging position.

11. The jointed bracelet of claim 10, in which said stop portion is adjacent the inside of the mouth at the narrow end of a shell and said one of said operative portions extends to and engages the interior of said shell adjacent the large end thereof thus limiting the movement of said spring relative to said shell in the opposite direction.

12. The jointed bracelet of claim 10, in which said stop portion is within one shell and adjacent the outside of the open mouth at the small end of an adjacent shell, and in which said other of said operative portions engages a structural element in said adjacent shell, thus limiting the movement of said spring relative to said shells in the opposite direction.

13. The jointed bracelet of claim 10, in which said stop portion is within one shell and adjacent the outside of the open mouth at the small end of an adjacent shell, and in which said other of said operative portions engages around the pivotal connection between said adjacent shell and the next adjacent shell, thus limiting the movement of said spring relative to said shells in the opposite direction.

14. In a jointed bracelet comprising a plurality of hollow shells having large and small ends and with open mouths at said ends, the open mouth at said large end having a dimension greater than the corresponding dimension of the open mouth at said small end, the small end of one shell being received inside the large end of an adjacent shell and pivotally mounted therein about an axis substantially perpendicular to the longitudinal axis of said bracelet; the improvement which comprises springs active between said shells so as to urge them into a wrist-engaging position, said springs each comprising a pair of coiled portions, a pair of divergent arms extending from said coiled portions in one direction, and a reversely bent section joining said coiled portions and extending therefrom in a direction opposite from said arms and in a plane out of line with the planes of said arms, said coiled portions being passable through the open mouth at the large end of a shell but not being passable through the open mouth at the small end of said shell, said spring being positioned so that said coiled portions are adjacent the inside of the mouth at the narrow end of a shell, thus limiting its movement relative to said shell in a direction toward said mouth, said divergent arms engaging the inside of said shell at the large end of the open mouth thereat, thus limiting the direction of movement of said spring in the opposite direction with respect to said shell, and said reversely bent section extending through the open mouth adjacent said coiled portions, into the adjacent shell and engaging said adjacent shell, said reversely bent portion being received in said adjacent shell between the divergent arms of the next adjacent spring.

15. In combination with the jointed bracelet of claim 10, in which said stop portion of said springs comprise coiled portions, a hollow terminal shell of shape comparable to the other shells but having an open mouth only at the small end thereof, said small end being received within and pivotally mounted with respect to the last of the other shells of said bracelet, and a spring comprising a coiled portion and a pair of operative portions extending in opposite directions from said coiled portion and at angles to one another, said coiled portion being positioned within the last of the other shells, one of said operative portions being engaged with coiled portion of the spring in said last of the other shells, and the other of said operative portions extending into and operatively engaging said terminal shell, said spring being active on said terminal shell so as to urge it into a wrist-engaging pivoted position.

16. In combination with the jointed bracelet of claim 11, in which said stop portion of said springs comprise coiled portions, a hollow terminal shell of shape comparable to the other shells but having an open mouth only

at the small end thereof, said small end being received within and pivotally mounted with respect to the last of the other shells of said bracelet, and a spring comprising a coiled portion and a pair of operative portions extending in opposite directions from said coiled portion and at angles to one another, said coiled portion being positioned within the last of the other shells, one of said operative portions being engaged with the coiled portion of the spring in said last of the other shells, and the other of said operative portions extending into and operatively engaging said terminal shell, said spring being active on said terminal shell so as to urge it into a wrist-engaging pivoted position.

17. In combination with the jointed bracelet of claim 12, a hollow terminal shell of shape comparable to the other shells but having an open mouth only at the small end thereof, said small end being received within and pivotally mounted with respect to the last of the other shells of said bracelet, and a spring comprising a stop portion and a pair of operative portions extending in opposite directions from said stop portion and at angles to one another, said stop portion being positioned within the last of the other shells, one of said operative portions being engaged with the stop portion of the spring in said last of the other shells, and the other of said operative portions extending into and operatively engaging said terminal shell, said spring being active on said terminal shell so as to urge it into a wrist-engaging pivoted position.

18. In combination with the jointed bracelet of claim 14, in which said stop portion of said springs comprise coiled portions, a hollow terminal shell of shape comparable to the other shells but having an open mouth only at the small end thereof, said small end being received within and pivotally mounted with respect to the last of the other shells of said bracelet, and a spring comprising a pair of coiled portions, a pair of divergent arms extending from said coiled portions in one direction and having fingers projecting therefrom, and a reversely bent section joining said coiled portions and extending therefrom in a direction opposite from said arms and in a plane out of line with the planes of said arms, said coiled portions being positioned within the last of the other shells, said arms being received alongside, and said fingers engaging inside, the coiled portions of the adjacent spring in said last of the other shells, and said reversely bent section extending into and operatively engaging said terminal shell, said spring being active on said terminal shell so as to urge it into a wrist-engaging pivoted position.

19. A jointed bracelet comprising a plurality of hollow elements pivotally secured to one another, adjacent ends of said elements having aligned openings therethrough, at least one of which openings is defined at least in part by walls of said elements, abutments being defined on both sides of said opening, and a spring passing through said openings and operatively engaging said shells so as to urge them into a wrist-engaging pivoted position, said spring having portions bent out therefrom to a degree greater than the size of at least one of said end openings and on both sides of said one of said one openings, said spring portions operatively engaging said abutments at least one of said element ends so as to limit the movement of said spring longitudinally of said bracelet in both directions.

20. The jointed bracelet of claim 19, in which said spring extends to an appreciable length longitudinally through each of said elements, at least one of said bent out portions being integral at both ends with the body of said spring and being resiliently flattenable to facilitate insertion or removal of said spring.

21. In a jointed bracelet comprising a plurality of hollow elements having adjacent telescoped ends pivotally secured to one another, the inner telescoped end having an opening of restricted size therethrough, defined at least in part by walls of said element, abutments being de-

11

fined on both sides of said opening, and a spring passing through said opening and operatively engaging said elements so as to urge them into a wrist-engaging pivoted position; the improvement which comprises spring having portions bent out of the general longitudinal axis of said bracelet to a degree greater than the size of said opening and positioned on both sides of said opening, said spring portions operatively engaging said abutments at said inner telescoped end so as to limit the movement of said spring longitudinally of said bracelet in both directions.

22. The jointed bracelet of claim 21, in which said spring extends to an appreciable length longitudinally through each of said elements, at least one of said bent out portions being integral at both ends with the body of said spring and being resiliently flattenable to facilitate insertion or removal of said spring.

23. A jointed bracelet comprising a plurality of hollow elements pivotally secured to one another, adjacent ends of said elements having aligned openings therethrough, and a spring passing through said openings and operatively engaging said shells so as to urge them into a wrist-engaging pivoted position, said spring having portions bent out therefrom to a degree greater than the size of at least one of said end openings and on both sides of said one of said end openings, said spring portions operatively engaging at least one of said element ends so as to limit the movement of said spring longitudinally of said bracelet in both directions, said spring extending to an appreciable length longitudinally through each of said elements, at least one of said bent out portions being integral at both ends with the body of said spring and

12

being resiliently flattenable to facilitate insertion or removal of said spring.

24. In a jointed bracelet comprising a plurality of hollow elements having adjacent telescoped ends pivotally secured to one another, the inner telescoped end having an opening of restricted size therethrough, and a spring passing through said opening and operatively engaging said elements so as to urge them into a wrist-engaging pivoted position; the improvement which comprises said 10 spring having portions bent out of the general longitudinal axis of said bracelet to a degree greater than the size of said opening and positioned on both sides of said opening, said spring portions operatively engaging said inner telescoped end so as to limit the movement of said spring 15 longitudinally of said bracelet in both directions, said spring extending to an appreciable length longitudinally through each of said elements, at least one of said bent out portions being integral at both ends with the body of said spring and being resiliently flattenable to facilitate insertion or removal of said spring.
